UNITED STATES PATENT OFFICE.

MINARD A. POSSONS, OF CLEVELAND, OHIO; ASSIGNOR TO AMERICAN STOVE COMPANY, OF ST. LOUIS, MISSOURI, A CORPORATION OF NEW JERSEY.

OVEN CONSTRUCTION.

Application filed April 15, 1926. Serial No. 102,145.

This invention relates to improvements in oven constructions and it refers particularly to a construction that eliminates the ordinary separate door frame.

5 So far as applicant is aware it has been common heretofore to have what has been termed in the art as separate door frames, and the primary object of this invention is to so construct the oven that a separate frame for its doors is eliminated.

10 A further object of the invention is to construct the side and top walls of the oven that they constitute indented means that act as a stop for the inward movement of the oven door.

15 A further object of the invention is to have this frame arrangement constructed integral with the top and side walls of the oven structure.

20 A further object of the invention is to have this integral portion of the side and top walls form a recess that is substantially as deep as the thickness of the door to furnish an even external surface of the door 25 with the surrounding bead.

A further object of the invention is to construct an oven having its top and side walls formed integral with inwardly and laterally bent portions that form a recess to 30 receive the door, the said recess having a narrow surrounding bead portion.

35 A further object of the invention is to construct the oven with separately detachable top and side walls whereby these parts can be enameled, leaving only a narrow surrounding finishing bead that is substantially black, and whereby should the enamel become broken on any part, it can be removed and another wall substituted therefor.

40 A further object of the invention is broadly to construct an oven that has its side and top walls enameled to furnish a finished enameled product with only a narrow finishing bead of another color surrounding the said doors.

45 A further object of the invention is to construct the top and side walls of an oven with integral inwardly bent portions against which the door is closed, the side 50 walls extending from top to bottom of the wall, and a narrow connecting piece attached

at its ends to the said walls between the oven and broiling doors.

Further objects of the invention involving details of construction will appear from 55 the following description:

Figure 1 is a perspective view of an oven which embodies my present invention.

Figure 2 is a vertical sectional view along the line 2-2, showing the doors in 60 position, the said oven being intermediately vertically broken.

Figure 3 is a vertical sectional view on the line 3-3 of Figure 1.

Figure 4 is a horizontal sectional view on 65 the line 4-4 of Figure 1.

Figure 5 is a horizontal sectional view on the line 5-5 of Figure 1.

Figure 6 is an enlarged sectional view on 70 the line 6-6 of Figure 1.

Figure 7 is a detached view of the parts involving the present invention arranged in separated relation for the purpose of showing the specific construction of parts.

Figure 8 is a perspective sectional view on 75 the line 8-8 of Figure 7 looking in the direction indicated by arrow.

Figure 9 is a detached front perspective view of part of the top of the oven.

Figure 10 is a horizontal sectional view 80 taken through Figure 6 just above the clamping bolt 10' looking downwardly.

In carrying out the above defined ideas the front edges of the top wall 1 and the side walls 2 of the oven are specially constructed. The special construction of these walls is shown in Figures 2, 4, 5 and 6.

The special construction forms recesses to receive the oven door 5 and the broiler door 6, when the latter is used.

Usually in ovens a separate front or door frame is used, the said frame provided with door openings. In the construction here shown, the separate front frame or frames are completely eliminated. I accomplish 95 this elimination by having the front edge of these walls with integrally formed constructions. For instance the front edges of both the top and side walls are doubled at right angles to the said walls, as shown at 100 11, which is in a plane with the face of the oven which walls are then doubled inward

at right angles as shown at 8, then again doubled at right angles in a line with the face of the oven as shown at 9, and again doubled inward at right angles as shown at 10.

These parts as here shown are preferably integral with the walls 1 and 2. By doubling these walls as described, first a narrow outer face 11 is formed around the doors, and a recess 12 is formed in a direction parallel with the doors and the front face of the oven. This recess 12 preferably extends entirely around the face of the oven, and the depth of this recess is regulated by the length of the doubled or leg portion 8. This leg portion 8 is preferably of a length equal to the thickness of the door whereby the door when it is closed in the said recess, is flush with the surrounding rim portion 11. The object of bending inward the inner edge of the recess 12 as shown at 10 is for giving the said portion strength and rigidity to maintain its shape.

By reference to Figure 7, it will be noted that the upper end of the doubled portion of the side walls 2 is bent inward a slight distance as at 13 sufficient for the wall of the top portion 1 to fit this doubled portion of the side wall, and where these parts overlap they are provided with registering bolt openings 14 and 15 through which a suitable bolt 10' passes for fastening the parts together.

The inwardly bent portion 13 extends across the upper end of the wall 12 and also the upper end of the surrounding rim portion 11. To add rigidity to the side wall 2 its upper end is bent horizontally inward as at 26, and the front end of this inwardly bent part or flange 26 is cut away as shown at 27 for the purpose of enabling the bent portions 8, 9 and 10 to be formed in the front vertical edge of the side wall 2.

Usually ovens are provided at their lower portions with what is termed in the art as the broiler part of the oven. When the oven is provided with this usual broiler portion as here shown, the door openings are controlled by the broiler door 6. In such an instance I provide a cross member 16 that is so shaped as to fit the irregular bent portion of the side walls and to extend out in the same plane as the narrow rim 11, and will have substantially the same exposed width 17 as the width of the rim 11. This cross piece 16 has its lower edge recessed as shown at 18 a distance equal to the recess 12, whereby a complete closing recess for the broiler door 6 is provided, while the upper face 19 of the cross piece 16 closes tightly with the lower edge of the oven door 5. This cross piece 16 is preferably composed of cast metal, its inner edge being essentially U-shaped as illustrated at 20. The ends of this cross piece 16

are cut out to receive the wall of 65 the recess 12, and it is held in this position by a screw that passes through a reinforcing strip 21 and the wall of the recess 12, the said parts having registering screw openings 22 and 23, and the screw 24 passes 70 through these pieces and into an opening 25 formed in the cross piece 16. In that manner the cross piece, the reinforcing strip 21 and the wall 12 are united detachably together. As here shown the outer edge 28 of 75 the reinforcing strip 21 is bent laterally outward as shown in Figure 5, resting against the inner side of the bent portion 8.

By referring to Figures 6 and 7 it will be observed that in forming the openings 14 and 15, the periphery of the openings are countersunk, and that the head of the screw or bolt 10' is made flat and fits in the countersunk portion of the opening. In this way the head of the bolt is flat with the surface 12, and does not interfere at all with the closing of the door 5.

Referring now to the top part 1, its front horizontal edge is formed to correspond with the formation of the vertical edge of the 90 side wall 2, and are so constructed that there is formed a horizontal wall corresponding to the wall 12 against which the door closes. The sides 29 of the top portion are turned downward and rest outside of the upper part 95 of the side walls 2, while the rear edge 30 is also bent downward to receive the upper inwardly bent end 31 of the rear wall 32 of the oven 2.

A separate splash side board 33 is arranged 100 between the top 1 and the open burner frame 34. This is located at the upper part of the side wall 2, and is enameled to correspond to the enameling of the doors 5 and 6, the top wall 1 and the outer side wall 2. In this manner the wall 33 is made detachable whereby it can be separately enameled and then applied to the oven. The front end 35 of the wall 33 is formed into an outwardly bent bead portion, the outer edge 36 of this bent 110 portion extending into a vertical groove 37 made in the side wall 2 of the oven. The object of this construction is to make the outer edge of the wall 33 fit tightly the wall 2 and to conceal the outer edge 36. The lower edge 115 38 of the wall 33 as shown by dotted line in Figure 1, passes downward between the adjacent wall of the open burner frame 34 while its upper edge 39 extends upward between the part 29 of the top 1 and the upper end of the side wall 2. This manner of holding the wall 33 in position avoids the necessity of bolts of any kind for that purpose, while at the same time it insures that the said 120 wall will be held tightly against the wall 2. The rear end of the wall 33 is preferably provided with an outwardly bent bead por- 125 tion 40 that is similar to the part 35 at its

front end and which also fits into a groove similar to the groove 37 that is made in the front end of the wall 2.

For the purpose of making a finish for the rear end of the top 1, I provide a vertically arranged U-shaped member 41 that has its lower end 42 L-shaped and which is held to the described parts of the oven by means of suitable bolts 43.

10 It will be understood from the foregoing description that the inwardly bent flange on the top portion 1 corresponding to 10, is cut away a short distance and also that part corresponding to 11 and 8 cut away to enable the 15 top portion to be properly placed in position on the side of the walls to bring the surrounding wall 12 flush all around.

By forming the front edges of the side walls and of the top walls in the manner herein described, it will be observed that I have entirely eliminated the necessity for a detachable door frame, while at the same time I have provided a recess sufficiently deep to receive the oven doors and to produce a strong structure with a finished appearance. I also am enabled to make a structure that is relatively deep as compared to the ordinary structure.

20 I am also enabled to produce a stove which in appearance is without any front frame and to produce an oven that is wholly enameled.

One advantage of the above defined and illustrated construction as compared with the usual ovens, is that all visible bolts and fastenings are omitted from the structure. This makes quite a reduction in the cost of assembling of the structure, as well as in the production of it.

40 It will be noted in examination of that part of Figure 7 which shows the side wall bent as described, that the bends 8, 9 and 10 make a contour that is substantially Z-shaped.

45 While I have described and have shown many details of construction, I wish it understood that variations may be made in this construction without departing from the spirit and scope of my invention so long as the changes would come within a fair interpretation of the appended claims.

Having thus described my invention, what I claim and desire to secure by Letters Patent of the United States is:

55 1. An improved oven door structure and door therefor, comprising separate top and side portions having their front edges bent inwardly and laterally to form a surrounding bead and a door seat, the separable top and sides constructed to telescope, means for securing the top and sides in position, and a door of a size to be seated within the said bead portion for the purpose described.

60 2. An oven structure and door therefor, said structure having its top and side por-

tions bent inwardly and laterally forming a bead portion and a seat for the said door, the inwardly bent portion of one part of said structure being cut away a distance equal to the bead portion whereby the side 70 and top parts may telescope, and a door of a size fitting within the said head portion.

3. An oven structure and a door therefor, the said structure having its top and side portions bent inwardly and laterally forming an exposed bead portion and a seat for the door, the side portion having its top bent inwardly and the outer end thereof cut away for the purpose described.

4. An oven structure and a door therefor, the oven structure composed of separate top and side portions, said top and side portions being bent inwardly and laterally to form a bead and a seat for the door, said laterally bent portions of the top and side 85 telescoping, and means passing through the said telescoping parts for securing them together, and a door adapted to be seated within the said bead portion.

5. An oven structure and a door therefor comprising separate top and side portions bent inwardly and laterally forming an exposed bead portion and an inwardly extending seat for the door, the upper ends of the laterally bent portion of the sides deflected inwardly whereby the correspondingly inwardly bent portion of the top forms a flush seat for the door, and a door of a size to fit within the said bead portion.

6. An improved oven structure comprising top and side walls having their front ends inwardly bent to constitute an inwardly extending door receiving recess, the inner side wall provided with a vertical indentation, and a sub-wall having its front edge inwardly bent to fit in the said indentation and means for securing the parts together.

7. An improved oven structure comprising top and side walls having their front edges inwardly bent to constitute an inwardly extending recess adapted to receive an oven door, the side wall having at its front edge a vertical indentation and a sub-wall having its front edge adapted to enter the said indentation for the purpose described, the top and bottom edges of the said sub-wall held in position by the top of the oven and by an open burner frame.

8. An oven structure comprising top and side walls and a door therefor, the front edges of the top and side walls bent inwardly and laterally constituting a surrounding bead and a seat for the door, the side edges of the top turned downwardly and telescoping the upper edges of the side walls, and a door of a size fitting within the said bead portion.

9. An oven structure and a door therefor, the top and side walls of the structure having their front edges bent inwardly and lat-

- erally forming a surrounding bead and a seat for the door, the top having its side edges bent downwardly and telescoping the top edges of the said walls, the inner side wall having near its front edge a vertical recess and a sub-side wall having its front edge curved inwardly fitting in the said recess and its upper edge also embraced by the depending flange of the top portion.
- 10 10. An oven structure and a door therefor, the top and side walls of the structure having their front edges bent inwardly and laterally forming a surrounding bead and a seat for the door, the top having its laterally bent portion cut away a distance equal to the width of the bead portion whereby it may telescope the side walls.
11. An oven structure and a door therefor, the top and side walls of the structure having their front edges bent inwardly and laterally forming a surrounding bead and a seat for the door, the top having its laterally bent portion cut away a distance equal to the width of the bead portion whereby it may telescope the side walls.

In testimony whereof I hereunto affix my signature.

MINARD A. POSSONS.
